(57) **CLAIM**

The ornamental design for a passive milk collection device, as shown and described.

DESCRIPTION

FIG. 1 is a front perspective view of a passive milk collection device showing my new design;

FIG. 2 is a front elevational view thereof;

FIG. 3 is a right-side view thereof;

FIG. 4 is a left-side view thereof;

FIG. 5 is a rear view thereof;

FIG. 6 is a top plan view thereof;

FIG. 7 is a bottom plan view thereof; and,

FIG. 8 is rear perspective view.

The broken lines depict portions of the article that form no part of the claimed design.

1 Claim, 8 Drawing Sheets
